UNITED STATES PATENT OFFICE.

JOHN G. FUYAT, OF TAUNTON, MASSACHUSETTS, AND TOUSSAINT FUYAT,
OF PROVIDENCE, RHODE ISLAND.

MACHINE FOR PRODUCING YARN OF DIFFERENT COLORS.

SPECIFICATION forming part of Letters Patent No. 320,344, dated June 16, 1885.

Application filed May 31, 1884. (No model.)

To all whom it may concern:

Be it known that we, JOHN G. FUYAT, of Taunton, in the State of Massachusetts, and TOUSSAINT FUYAT, of Providence, in the State 5 of Rhode Island, have invented an Improvement in Machines for Producing Yarn of Different Colors, of which the following is a specification.

Our invention has for its object the manufacture of thread or yarn of lengthwise alternating colors from previously-manufactured roving of different uniform colors; and it consists in the improved combination of intermittently-driven rolls and continuously-driven 15 rolls, and means for driving the said rolls, as hereinafter set forth.

Figure 1 is a front view of a portion of the rolls of a spinning-frame embodying our improvement. Fig. 2 is an end view of the rolls 20 showing the gears by means of which they are operated, one of the gears being broken away. Fig. 3 is a transverse section of the rolls. Fig. 4 is an elevation and partial section of the rear rolls. Fig. 5 is a detail drawing, partly in 25 section, showing an improved geared roll adapted for alternate movement. Fig. 6 represents a length of the yarn or thread of alternating different colors.

In the accompanying drawings, A represents 30 a portion of the frame of the spinning-machine, which constitutes a bearing for the rolls, the forward set of rolls, B B', being made for drawing and delivering the roving as usual in such machines. The rear set of rolls, C C' C 35 C', are specially constructed for carrying out our improvement, and are preferably made hollow and placed upon a central shaft, the alternate rolls C being secured to the shafts D and D' by means of the set-screws a a or otherwise, while the intermediate rolls, C' C', 40 (shown in section in Fig. 4) are arranged to revolve loosely upon the shaft. The fixed rolls C and the loose rolls C' are arranged in an alternating series upon the shaft D opposite to 45 that of the alternating series of the same rolls upon the shaft D', so that throughout the series a roll C fastened to the shaft D will be arranged opposite to a loose roll upon the opposite shaft, D', and the loose rolls upon one 50 shaft may be made to revolve by simple frictional contact with the periphery of the tight

roll upon the opposite shaft; or the two rolls may be provided with interlocking gear-teeth, by means of which motion will be imparted from the tight roll upon one shaft to the loose 55 roll upon the opposite shaft. In Figs. 1 and 3 the opposite rolls C C' are represented as being provided with a fluted surface, and in the detail view, Fig. 5, the adjoining rolls C C' are represented as being provided with a narrow gear, e, the gear e upon the tight roll of one series being adapted to gear into the gear e of the loose roll of the opposite series. 60

In order to provide for the separation of the rovings g g' in entering the rolls, the adjoining rolls C C' upon the shaft D are provided at their edges with annular grooves d, while the corresponding rolls upon the opposite shaft, D', are provided with the raised flanges e, 65 which are adapted to enter the grooves d of 70 the opposite rolls.

A modification of the rolls C C' is indicated by the dotted lines in Fig. 5, the surface of the rolls being thus made conical and provided with gear-teeth, which are of proper depth 75 and pitch on the outer side of the rolls, as in the gears e, but which are made to vanish at a point near the groove d or the flange.

The shafts D and D' and the fixed rolls C thereon are driven by means of the segmental gear E, secured to the shaft K of the lower delivering-roll, B, the teeth being removed from alternate quarter sections of the circumference of the gear, leaving the two opposite segmental gears, f f', the lower shaft, D', of the combining-rolls C C' being driven from the segmental gear E by 80 means of the intermediate gear, F, which engages with the gear G of the shaft D', and the upper shaft, D, of the combining-rolls C C' is driven from the segmental gear E by 85 means of the intermediate gear, H, and the gear I, which engages with the gear J, secured to the shaft D, the gears G and J being arranged in different vertical planes so that they will not engage with each other. The shafts 90 D and D' will thus be separately driven from the segmental gear E, and the gears F and H are so arranged relatively to each other that the shafts D and D' will be alternately at rest and in motion during the continuous revolution of the rolls B B', and when the spinning-machine is set in operation the roving will be 95 100

delivered to the spinning devices from the continuously-driven rolls B B'; but the rear rolls, by means of their alternately stopping and starting action, will cause the differently-colored rovings g and g' to be alternately fed to the rolls B B' and pulled asunder between the rolls B B' and the rolls C C', and by becoming united in the contracted passage through the guide h , which may be supported in position 5 by means of a stem, i , they will pass as a single roving, g^2 , of alternating colors between the rolls B B' to be thereafter twisted or spun into a single thread of alternating colors.

It will of course be understood that we do 15 not limit ourselves to the segment-gear for imparting an alternate intermittent motion to the shafts of the combining-rolls, as other devices may be advantageously employed for this purpose, and that other means may be 20 employed for causing the alternate feeding and separation of the differently-colored rovings.

We claim as our invention—

1. The combination of two adjoining pairs 25 of combining-rolls, and means for driving the same with an alternating intermittent or variable movement, with a pair of delivering-rolls and means for driving the same continuously, whereby the rovings of different colors will be alternately drawn forward or pulled asunder, 30 and joined into a single roving of alternating colors, substantially as described.

2. The combination of a shaft and a pair of 35 rolls arranged adjoining each other upon the same, the one fast and the other loose, with a shaft having an oppositely-arranged pair of fast and loose rolls thereon, whereby upon the stoppage or varied movement of either one of

the roll-shafts the loose roll thereon will be driven from the opposite shaft, and means for driving the said shafts, substantially as and 40 for the purpose specified.

3. The combination of the roll-shafts with the oppositely-arranged series of combining-rolls arranged in pairs, the one fast and the other loose on their respective shafts, a segmental driving-gear, means for driving the same, and means for communicating a forward rotary movement to the said roll-shafts alternately from the segmental driving-gear, substantially as described. 45

4. The combination of the roll-shafts and the opposite combining-rolls, the one fast and the other loose on their respective shafts, the one being also provided at its edge with a raised flange and the other with a corresponding groove, substantially as and for the purpose specified. 50

5. The combination of two adjoining pairs of combining-rolls, and means for imparting an alternate intermittent or variable movement to the same, with a pair of drawing and delivering rolls, and means for driving the same continuously, and a roving-guide arranged in the space between the combining and delivering rolls, whereby the rovings 60 drawn asunder by the alternate stoppage of the combining-rolls will be uniformly brought together to form a single roving, substantially as described. 65

JOHN G. FUYAT.
TOUSSAINT FUYAT.
